UNITED STATES PATENT OFFICE.

PAUL STEIFF, OF GIENGEN BRENZ, GERMANY, ASSIGNOR TO MARGARETE STEIFF, INC., OF NEW YORK, N. Y., A CORPORATION OF NEW YORK.

DESIGN FOR A STUFFED TOY ANIMAL OR SIMILAR ARTICLE OF MANUFACTURE.

Application filed March 5, 1929. Serial No. 30,327. Term of patent 7 years.

To all whom it may concern:

Be it known that I, PAUL STEIFF, a citizen of Wurttemberg, residing at Giengen Brenz, Kurze Strasse 1, Wurttemberg, Germany, have invented a new, original, and ornamental Design for a Stuffed Toy Animal or Similar Article of Manufacture, of which the following is a specification, reference being had to the accompanying drawing forming a part thereof.

The figure is a front perspective view of a stuffed toy animal showing my new design.

I claim:

The ornamental design for a stuffed toy animal or similar article of manufacture, substantially as shown.

PAUL STEIFF.
